UNITED STATES PATENT OFFICE.

ARTHUR W. PHIPPEN, OF METHUEN, MASSACHUSETTS.

ROOFING.

1,137,895.

Specification of Letters Patent.

Patented May 4, 1915.

Application filed January 15, 1914. Serial No. 812,289.

To all whom it may concern:

Be it known that I, ARTHUR W. PHIPPEN, a citizen of the United States, residing at Methuen, in the county of Essex and State of Massachusetts, have invented certain new and useful Improvements in Roofing, of which the following is a specification.

My invention relates to roofs of buildings and other structures and to devices for covering such roofs. It may also be used for covering railroad cars, vans or in fact any structure which has a roof exposed to the weather. It may also be used not only on new roofs but as a protecting covering for old roofs which are already covered with shingles or other material which have become so worn as to permit of leaks.

My invention is for use in connection with what is known as sheet roofing of any elastic kind such as rubberoid, tar paper or any of the other well known varieties which are more or less plastic.

For good results all parts of my device should be plastic and in connection with the sheet roofing, I prefer to use wooden cleats which have a tendency to swell in wet weather.

My device is particularly useful to lay over old shingled roofs without removing the shingles.

In the drawings, Figure 1 is an elevation of a portion of one side of an ordinary shingled pitch roof with my roof covering in place over the shingles. Fig. 2 is a vertical end sectional view of a roof similar to that shown in Fig. 1. Fig. 3 is an enlarged sectional view on the line X—Y of Fig. 1. Fig. 4 is a vertical end sectional view of my roof covering applied directly to the boards. Fig. 5 is an enlarged sectional view on the line S—T of Fig. 4.

A represents the roof boards of a wooden roof of well known construction.

In Figs. 1, 2 and 3, 10, 11, 12, 13 are wooden shingles of various overlapping courses of well known construction. In the construction shown in Figs. 1, 2 and 3, a plurality of strips of sheet roofing such as 20, 21, 22 are spread vertically from the ridge to the eaves, the edges being covered and fastened by cleats 30, 31. These cleats 30, 31 are given any desired ornamental shape at the top 33 and may be of any desired shape on the sides 34 and 35. At the bottom 36, they are flat and from the bottom is cut a longitudinal groove 37 which tapers

from its opening at the bottom inward toward its top 38. The outer edges or lips 39 should be rounded and I prefer also to round the top 38 so that there will be no rough corners.

I prefer to lay my roof covering by starting at one end of the side of the roof, where one edge of a strip of sheet roofing is firmly attached by cleats, by nails, by bending over the edge and tacking or in any other suitable way according to the style of the roof. A second strip is now brought up lengthwise against the free side of the first strip and the adjoining edges of both are placed together and bent upward as shown with 20 and 21 in Fig. 3. One of my cleats is now placed down over these adjoining edges and is forced thereon by pressure or pounding until they are crammed together into the tapering slot and are preferably forced into the top thereof where the ends are crowded together and so distorted that an absolutely weather tight joint is made. By means of suitable nails 24 preferably of the round wire variety, the cleats are fastened into place on top of the shingles and the roof boards A.

The edges of strips 20 and 21 should be bent up sufficiently so that they will reach the top of the slot 37, and the slot should be of such width that it will receive a double thickness of the said roofing but tapers to a point where it is preferably slightly less in size than two thicknesses. By this construction the plastic or elastic roofing is wedged together inside the slotted cleats which are then firmly fastened in place and after the first and second strips are so laid, the other strips are similarly laid until the other end of the roof is reached. This end is treated in a manner similar to the first end mentioned. The roof now has a series of narrow vertical channels down which the water can travel, separated by weather tight joints which become tighter and tighter after the wood of the cleats swells. As will be seen, old shingled roofs can be covered in this way without removing the shingles and made weather tight while the shingles themselves and the air spaces between the courses help to keep the interior of the house warm.

In Figs. 4 and 5, I show a roof comprising roof boards A upon which are laid vertical strips of sheet roofing 40 and 41. The adjoining edges of these strips are bent

upward and placed together and over them is forced a cleat such as 43 which at the bottom has a longitudinal slot 44 similar to the slot 37 except that as shown it tapers to a lesser degree. The cleat in this case is nailed in place in a manner similar to that shown in Figs. 1, 2 and 3. In Figs. 4 and 5, the plastic sheet roofing is shown as having pebbles or similar material embedded in the 10 surface and is shown of a greater thickness than that in Figs. 1, 2 and 3.

With this construction, it is preferable to have the lips of the tapering slot rounded with a sweep or a curve of greater radius 15 than where thin stock is used so that the sheet will not break. It will also be observed that the pebbles where they come in contact with the cleat are forced into the roofing sheet. It is essential that the longitudinal slots should taper from the outside or lips inward in order to get a tight joint but this taper may not be very great.

In Fig. 3, the nails are shown as driven vertically through the cleat or molding 25 while in Fig. 5, they are shown as driven in diagonally from opposite sides.

In laying the roofing sheets, I prefer to crease the adjoining edges with a special tool before putting the cleat in place. I 30 prefer to turn up the edge half an inch or so as thereby any irregularity in the roof or any defect in the shingles is compensated for. If the roof were preferably even a less turn up would be sufficient.

With the tapering slots, the adjoining 35 edges of the roof sheets at the top are distorted and amalgamated, while the downward pressure of the cleat bellies the adjoining bent up faces of the sheet roofing and cause them to lie flat together as shown 40 in Figs. 3 and 5. Lying thus flat against each other, these adjoining faces make a tight joint even if it were not otherwise tight.

My roof covering requires the use of but 45 few nails, as the slotted cleats hold the parts together, and it requires no nails passing through the flat part of the sheet roofing. With nails driven in as shown in Figs. 3 and 5, there is no danger of leaking 50 through the nail holes. My joint is easy to make as it consists of one part only.

I claim:

In a roof covering, the combination of 55 roof boards, with a plurality of vertical strips of plastic sheet roofing the adjoining edges of which are bent upward, and wooden cleats which have at the bottom longitudinal tapering slots which are forced over the adjoining edges of the strips of roofing so 60 as to distort and amalgamate them.

In testimony whereof I hereto affix my signature in presence of two witnesses.

ARTHUR W. PHIPPEN.
